EDWIN CARRINGTON, OF WEST MERIDEN, CONNECTICUT.

Letters Patent No. 69,766, dated October 15, 1867.

IMPROVED DRAPERY-HOOK.

The Schedule referred to in these Letters Patent and making part of the same.

TO ALL WHOM IT MAY CONCERN:

Be it known that I, EDWIN CARRINGTON, of West Meriden, in the county of New Haven, and State of Connecticut, have invented a new improvement in Drapery-Hook; and I do hereby declare the following, when taken in connection with the accompanying drawings, and the letters of reference marked thereon, to be a full, clear, and exact description of the same, and which said drawings constitute part of this specification, and represent in—

Figures 1 and 2, the application of the hook.

Figure 3, a side view.

Figure 4, a front view of the hook, illustrating its operation.

Figures 5 and 6, single hooks.

Figures 7 and 8, double hooks; and in

Figures 9 and 10, the eye for attaching the hook.

This invention relates to an improvement in hooks for hanging drapery, such as window-curtains, &c, and consists in the peculiar construction of the hook, whereby the drapery may be securely attached and not accidentally detached.

In order to the clear understanding of my improvement, I will proceed to describe the same as illustrated in the accompanying drawings.

A, figs. 3 and 4, is the base of the hook, secured to the window, or wherever it is desired to attach drapery, by a screw, B, or other equivalent means. The hook is formed by a perforation through, as at a, and then slitting outward, as at d; the slot being of less width than the diameter of the perforation. In figs. 3 and 4 the hook is represented as large, for window-curtains and similar drapery, and to the curtain are fixed eyes C, their upper edge formed sufficiently thin to pass through the slot into the perforation, being inserted in the position denoted in red, fig. 3, and when they have passed on to the perforation or enlarged opening are turned down, as denoted in black. The eye cannot be removed until turned up to the position denoted in red, which position cannot be accidentally attained.

For curtains it is generally necessary that a double hook be used, such as is shown in figs. 3 and 4, and smaller in figs. 7 and 8; but for some purposes a single hook, as shown in figs. 5 and 6, may be all that is required. Those shown in figs. 5, 6, 7, and 8, are adapted to the use of the common dress eye for attachment to the hooks.

Having thus fully described my invention, what I claim as new and useful, and desire to secure by Letters Patent, is—

The herein-described drapery-hook, formed by an upward-inclined slot, d, opening into a recess, a, in the metal, of larger diameter than the width of the slot, and formed upon a base so as to be secured, substantially as specified.

EDWIN CARRINGTON.
